[57] **CLAIM**

The ornamental design for a dual compartment carton, as shown and described.

DESCRIPTION

FIG. 1 is an inside perspective view of a dual compartment carton showing my new design in an open position;

FIG. 2 is a plan view on a reduced scale;

FIG. 3 is a bottom plan view thereof;

FIG. 4 is a side elevational view thereof;

FIG. 5 is an end elevational view thereof;

FIG. 6 is a perspective view in a partially closed position of a modified form of my new design, which differs from the embodiment of FIG. 1 only in the provision of the center slot shown;

FIG. 7 is a perspective view in a closed position showing a second modified form of my new design, which differs from the embodiment of FIG. 1 only in the provision of a segmented flap on the outside of each half of the carton;

FIG. 8 is a perspective view of the carton of FIG. 7 folded back on itself;

FIG. 9 is a bottom plan view of the carton as seen in FIG. 8; and

FIG. 10 is a perspective view of a third modified form of my new design with the segmented flaps engaged and which differs from the embodiment of FIG. 1 only in the provision of a center slot and two segmented flaps.
